ATTORNEYS

UNITED STATES PATENT OFFICE.

THOMAS WALL, OF BROOKLYN, NEW YORK, ASSIGNOR TO HIMSELF AND ROBERT SEALY, OF SAME PLACE.

BURNER FOR STREET-CAR LAMPS.

SPECIFICATION forming part of Letters Patent No. 440,079, dated November 4, 1890.

Application filed January 24, 1889. Serial No. 297,438. (No model.)

To all whom it may concern:

Be it known that I, THOMAS WALL, of the city of Brooklyn, county of Kings, and State of New York, have invented a new and useful Improvement in Lamp-Burners, of which the following, taken in connection with the accompanying drawings, is a full, clear, and accurate description.

In the drawings, Figure 1 represents a side view of a burner with my improvement attached. Fig. 2 is a sectional view of my invention. Fig. 3 is a side view of the screw-cap of the burner as applied to my invention. Fig. 4 is a view of the locking collar or nut, 15 constituting part of my invention.

Similar letters of reference refer to similar parts.

My invention relates to burners for street-car lamps; and the construction of the lamp-boxes is such that the lamp-founts are twice as long as they are wide. The lamp-boxes have reflectors placed at an angle on the inside and where the length of the box is the greatest.

It is important to obtain the greatest candle-power possible, and in order to accomplish this the burner ought to be adjusted to the lamp-fount, so that the wick-tube shall stand parallel with the length of the said lamp-fount.

The lamp-burners in use on street-cars are adjusted to the fount by screw-threads cut on the lower portion of the burner and corresponding screw-threads cut in the collar of the lamp-fount, so that when the burner is securely fastened to the lamp-fount it often happens that the wick-tube will be at an angle instead of being parallel with the length of the lamp-fount, as it properly should be.

The object of this invention is to construct a lamp-burner so that at all times the wick-tube can be easily adjusted parallel with the length of the lamp-fount. I accomplish this result by making that portion of the burner bearing the screw-thread about twice the usual length. I make another part or portion, independent of the burner, having corresponding screw-threads cut on the inside of

it, so as to be adjusted to that portion of the burner bearing the screw-threads, answering 50 the purpose of a locking collar or nut. The outside of the separate portion or part is milled, so that it is more easily handled when it is to be adjusted.

In the drawings, A represents the part of 55 the burner which is fitted or screwed into the collar of the lamp-fount, a being the screw-threaded portion thereof.

B is the detachable locking collar or nut, containing the screw-thread b, cut on the inside and fitting into the screw-thread a on the cap-piece A.

The operation of my invention is as follows: The detachable nut or locking-collar B is screwed upon the cap A. Then in order to adjust my improved burner the burner is first screwed into the collar of the lamp-fount in the usual way. When properly secured in its position, if it is found that the wick-tube is not parallel with the length of the lamp-fount the burner is partially unscrewed from the collar of the lamp-fount and the detachable screw-threaded locking collar or nut B is screwed or turned in an opposite direction for a short distance, and the burner is then 75 screwed down into the collar of the lamp-fount. It will be found that this operation has changed the position or angle of the wick-tube to the length of the lamp-fount. By renewing this operation the wick-tube can be 80 brought parallel with the length of the lamp-fount.

Having thus described my invention, what I claim as new, and desire to secure by Letters Patent, is—

A lamp-burner having a screw-threaded portion, by which it is secured to a lamp, provided with a locking collar or nut working on said screw-threaded portion, substantially as described.

In testimony whereof I have hereunto set my hand.

THOMAS WALL.

In presence of—
LOUIS W. FROST,
ROBERT SEALY.
